ADJUSTABLE BRASSIÈRE

Ruth Freedman, New York, N. Y.

Application September 16, 1937, Serial No. 164,107

1 Claim. (Cl. 2—42)

This invention relates to an adjustable brassière and is a continuation and an improvement of the invention for combined brassière and bathing suit described in my application filed September 16, 1936, Serial No. 101,016.

The object of the invention is the production of an adjustable brassière, which can be easily fitted to the wearer.

The second object of the invention is the production of a brassière constructed to easily support the breasts of the wearer and space them from each other and the wearer.

~~The third object of the invention is the production of a brassière adapted to support other garments.~~

The fourth object of the invention is the production of a brassière which can be adjusted vertically and horizontally.

In the accompanying drawing Fig. 1 represents a rear elevation of the improved brassière, with a girdle detachably connected thereto; Fig. 2 shows an interior elevation of the brassière in its unfolded position; Fig. 3 indicates a section of Fig. 2 in the line 3, 3; Fig. 4 is a section of Fig. 2 on the line 4, 4; Fig. 5 represents an enlarged section of Fig. 2 on the line 5, 5; Fig. 6 indicates an enlarged section of Fig. 2 on the line 6, 6; Fig. 7 shows an enlarged section of Fig. 2 on the line 7, 7; Fig. 8 indicates an enlarged section of Fig. 2 on the line 8, 8; Fig. 9 represents an enlarged fragmentary portion of Fig. 2 and Fig. 10 is a section of Fig. 9 on the line 10, 10.

The brassière comprises the body portion designated in its entirety by the numeral 20, cut on the bias and preferably of broadcloth, silk or satin and the like, having the wave shaped lower edge 21 and the upper end with the central curved edge 22, the inclined edges 23 and the end curved edges 24. The edges 24 may be provided with elastic bands 24a. At the ends of the body portion 20 are indicated the inclined hems 25.

The body portion 20 is folded at the central openings 26, to form the return folds 27, to produce the spherical shaped outwardly extending pockets 30, for the breasts of the wearer. The body portion 20 and the folds 27, are stitched together by the stitches 31.

Through the wall of each pocket 30 extends the circular or oval opening 33, which cuts off the upper portion of the return folds 27 and may be covered with the netting 34.

The body portion 20 comprises the outer portions 35, the central portion 36 and the intermediate portion 37.

55 The portions 35 and 37 are connected by the

reinforcing seams 38 and the portions 36 and 37 are connected by the reinforcing seams 39. Curved strengthening bands 40 extend from the edges 23, over a portion of the contour of each pocket 30, to the upper ends of the seams 39. A 5 curved strengthening band 42 on the contour of each pocket 30 is fastened to the body portion 20 and below its adjacent band 40 and is also sewed to the latter. The ends of the bands 42 extend to the edges 22 and 23 of the body portion 20.

A pair of separating bands each comprises the horizontal portion 46 and the curved upwardly extending portion 47. A piece of elastic material 48 is preferably connected to the end of each portion 46 and is sewed to the adjacent reinforcing seam 38. The pieces of elastic material 48 may be omitted and the portions 46 may be directly sewed to their adjacent seams 38.

The upper end of each curved portion 47 is fastened to the body portion 20 adjacent to is edge 22 and the whole or the main part of the lower edge of the portion 47 is sewed to the band 42. The upper edge of each horizontal portion 46 is bound with a ribbon adjusting band 50, that encloses a cord 51 which latter is fastened in place. 20 The end portion 52 of each band 50 is closed and loose from the body portion 20, and may be fastened to the edge 22 of said body portion 20 for various adjustments by sewing or other fastening means as safety pins. It will be noted that when the brassière is fitted in place on the wearer, the loose end portions 52 of the adjusting bands 50, can be pulled in vertical directions or at angles thereto to raise or raise and horizontally space the breasts of the wearer in required positions. 35

A band 53 of non-stretchable material is fastened to the outer surface of the body portion 20. To one end of the band 53 is connected the elastic belt portion 55 having the eyes 56 and 56a, and the hem 25 at the other end of the body portion 20 is provided with the hooks 57. The latter engage the eye 56 or 56a when the brassière is in place on the wearer.

Eyes 58 may be fastened to the lower edge of 45 the body portion 20.

A pair of shoulder straps are each indicated in its entirety at 60. Each of the shoulder straps comprises the members 63 and 64 stitched to each other. Each shoulder strap 60 is padded at about 50 its central portion as indicated in Figs. 2 and 5. The padding comprises a strip of felt 65 and a ribbon 66 bears against the strip of felt. Both the latter are stitched to the shoulder straps as indicated. One end 68 of each shoulder strap 60 55

is stitched to the upper end of the body portion 20 at the edge 24.

At the junction of the edges 22 and 23 is indicated for each shoulder strap 60 one member 70 of a triangular brace and the second member 71 of the said brace has its lower end stitched to the body portion 20 at its edge 22. The said members 70 and 71 at the upper portions overlap each other to form an eye 74, and the members 70 and 71 below said eye 74 are stitched to each other as indicated at 75.

A buckle is indicated having the horizontal members 80 and 81 and the vertical connecting members 82. The member 80 extends through the eye 74. On the member 81 is pivotally supported a clamping member having the tubular portion 85 from which latter extends the gripping member 86 and the operating member 87.

Each of the shoulder straps 60 is led between the gripping member 86 and the outer face of the member 71 of its adjacent triangular brace. The lower end of each shoulder strap 60 is formed into a loop having the members 90 and 91. The member 90 of the loop at its upper end is fastened to the members 70 and 71 by the stitching 76. The member 91 is led between the outer face of the eye 74 and the gripping member 86. When the shoulder straps 60 are to be adjusted to different lengths, the operating members 87 are pulled up to be enabled to locate the said straps 60 between the gripping members 86 and the outer face of the eyes 74. When the shoulder straps are located in proper position, the user pushes down the operating members 87 and the gripping members

86 will grip the shoulder straps and hold them in place. By means of the construction just described the loops of the straps are maintained in place to be easily grasped.

If desired a girdle 95 may be connected to the lower edge 21, of the body portion 20, by means of the hooks 96 and the eyes 58.

Attention is called to the openings 33 through the pockets 30, to avoid annoyance to the breasts by the return folds 27, and to allow smoothness to the outer garments of the wearer.

The elastic bands 24a of the body portion 20 of the brassière provide means for preventing the edges 24 cutting into the flesh of the wearer.

Having described my invention I claim:

A brassière comprising a body portion having outwardly extending pockets, a separating band for each pocket comprising a horizontal portion and a curved upwardly extending portion, the end of each horizontal portion connected to said body portion and the curved upwardly extending portion of each band extending over a portion of its coacting pocket with its lower edge connected to the body portion of the brassière at the contour of its pocket, a ribbon adjusting band having its ends stitched to the upper edge of each separating band for a portion of its length, and a cord enclosed by each of said ribbons, each ribbon adjusting band with its cord adapted to have its ends adjacent to the upper edge of the body portion connected to the latter in different positions for adjustment.

RUTH FREEDMAN.
